UNITED STATES PATENT OFFICE.

EUGENE L. HOWE, OF MUSKEGON, MICHIGAN, ASSIGNOR TO STANDARD MALLEABLE IRON COMPANY, OF MUSKEGON, MICHIGAN, A CORPORATION.

PIPE BRACKET OR SUPPORT.

No. 884,661.

Specification of Letters Patent.

Patented April 14, 1908.

Application filed February 6, 1908. Serial No. 414,492.

To all whom it may concern:

Be it known that I, EUGENE L. HOWE, a citizen of the United States, residing at Muskegon, in the county of Muskegon and State of Michigan, have invented certain new and useful Improvements in Pipe Brackets or Supports, of which I do declare the following to be a full, clear, and exact description, reference being had to the accompanying drawing, forming part of this specification.

The present invention has relation more particularly to that class of brackets or supports designed for sustaining overhead heating pipes, such as are now commonly used in factory buildings or like situations.

It has heretofore been customary to form brackets or supports, of the class to which my invention relates, of cast metal, said supports being provided with a series of seats 20 wherein the pipes will rest, and with a series of openings extending between said seats for the purpose of lightening the casting and, when necessary, to admit additional sustaining bolts. A serious objection to such supports, as at present constructed from ordinary cast iron, is that they are apt to be easily broken when being set in position, or in case they are dropped from an elevation. Moreover, inasmuch as those parts of such 30 brackets or supports beneath the pipe seats have been formed solid, while the portions of the supports or brackets between the seats have been formed hollow, an inequality of strength has necessarily resulted.

My present invention is designed to provide a lighter and more durable pipe bracket or support which cannot be easily broken and which shall be of substantially uniform strength throughout.

To this end, my invention consists primarily in forming the bracket or support of a malleable iron casting with a plurality of hollow extensions and concave seats in its upper portion to receive the pipes to be supported, 40 said casting being chambered beneath said seats and being so constructed that its walls shall be of approximately uniform thickness. By thus forming the bracket or support, the following advantages result: first, the approximately uniform thickness of the walls of the casting avoids the danger of unequal shrinkage of the metal in the casting operation and lessens the danger of the warping,

distorting or cracking of the metal; second, a uniform strength is given to the casting since, 55 the walls being comparatively thin, the annealing operation will affect substantially the whole body of the metal of which the casting is formed; and, third, the bracket or support is rendered very light and this is of advantage, not merely in the matter of first cost, but also in that it lessens the cost of transportation.

Figure 1 is a view in side elevation of a bracket embodying my invention, parts 65 being shown in central vertical section. Fig. 2 is a plan view of a portion of my improved bracket or support. Fig. 3 is a view in vertical section on line 3--3 of Fig. 1. Fig. 4 is a vertical section on line 4--4 of Fig. 1. Fig. 5 is a cross section on line 5--5 of Fig. 1.

As shown, my improved bracket is formed with a plurality of concave seats 1 adapted to receive the sections of pipe 2 to be sustained. At its ends my bracket or support 75 is formed with the vertical openings 3 through which will be passed the retaining bolts 4 whereby the bracket or support will be suspended from the overhead part to which it is connected. Between the concave 80 seats 1 are formed vertical openings 5 which serve to materially lighten the casting, and, beneath the seats 1, the casting is chambered as at 6. As will be seen, the chamber 6 has upwardly extending parts 7 that lead to the 85 openings 5. By forming the casting with the chamber 6 and openings 5, as above described, the walls of the casting may be made of approximately uniform thickness. The advantage of this is, as above stated, viz: 90 it enables the casting to be annealed or "malleableized" with a substantial uniformity throughout, and insures that while the casting shall be light, it shall at the same time be exceedingly strong and durable.

Having thus described my invention, what I claim as new, and desire to secure by Letters Patent, is:

1. A pipe support comprising a casting of malleable metal, the upper part whereof is formed with a plurality of hollow extensions and with intermediate concave seats to receive the pipes to be supported, said casting being chambered beneath said seats so that its walls are of approximately uniform thickness.

2. A pipe support comprising a malleable casting, the upper part whereof is formed with a plurality of hollow extensions and with intermediate concave seats to receive
5 the pipes to be supported, said casting being provided at its ends with vertical openings to admit retaining bolts and having a cham- ber extending beneath said seats, the walls of said casting being of approximately uniform thickness.

EUGENE L. HOWE.
